(57) **CLAIM**

The ornamental design for a bird feeder, as shown and described.

DESCRIPTION

FIG. 1 is a perspective view of a bird feeder showing my new design.

FIG. 2 is a front view of the bird feeder.

FIG. 3 is a rear view of the bird feeder.

FIG. 4 is a left side view of the bird feeder.

FIG. 5 is a right side view of the bird feeder.

FIG. 6 is a top view of the bird feeder; and,

FIG. 7 is a bottom view of the bird feeder.

The claim is directed to the solid lines shown and the surfaces shown with line shading. The surfaces shown without line shading, and all broken lines shown, illustrate portions of the bird feeder that form no part of the claimed design.
